UNITED STATES PATENT OFFICE.

TOZABURO SUZUKI, OF SUNAMURA, JAPAN.

VERTICAL BOILER.

No. 810,002.

Specification of Letters Patent.

Patented Jan. 16, 1906.

Application filed May 17, 1905. Serial No. 260,781.

To all whom it may concern:

Be it known that I, TOZABURO SUZUKI, a subject of the Emperor of Japan, residing at No. 401 Jibeishinden, Sunamura, in the county of Minami-Katsushika, in the Province of Tokyo, Japan, have invented certain new and useful Improvements in Vertical Boilers, of which the following is a specification.

10 My invention relates to vertical boilers.

My invention comprises generally a vertical boiler which is divided into a lower water-chamber, an upper evaporating-chamber, and an intermediate combustion-chamber, 15 the latter having inlet and outlet openings arranged to cause the products of combustion to travel in a horizontal plane from the inlet to the outlet.

My invention also comprises an improved 20 feed-water-heater intake, whereby the feed-water is heated after its admission to the boiler without being brought directly in contact and reducing the temperature of the water adjacent the heating-surface and steam-space.

Heretofore vertical boilers have been provided with a lower wall constituting the principal heating area against which the products of combustion are directed, the furnace being 30 located below the boiler. One of the great defects of this form is that incrustation, scale, and dregs descend and collect on the heating-surface, preventing contact of the water therewith and reducing the efficiency 35 of the boiler. This defect is very troublesome where the water used contains a large percentage of foreign matter. In my improved boiler by placing the flame-engaging or water-heating surfaces above the bottom 40 wall and causing the products of combustion to travel in a horizontal plane I avoid the necessity of frequent cleaning and can use the boiler for a great length of time without decreasing its efficiency. I am also able to use 45 any kind of water convenient, regardless of its condition, as the scale and dregs are never in contact with the heating-surface.

By the provision and general arrangement 50 of the feed-water intake I am enabled to partially heat the water when the same is introduced into the boiler, and I avoid bringing it into contact with and reducing the temperature of the water nearest adjacent the heating-surfaces and steam-space.

55 My invention will be more fully described in connection with the accompanying draw-

ings and will be more particularly pointed out in the appended claims.

In the drawings, Figure 1 is a vertical sectional view of a boiler embodying the main features of my invention. Fig. 2 is a horizontal sectional view of the same on line 2 2 of Fig. 1. Fig. 3 is a similar sectional view showing a modified form of construction. Fig. 4 is a horizontal sectional view of a structure including three distinct boilers of the form shown in Fig. 1 connected in a manner to utilize the products of combustion of a single furnace.

Like characters of reference designate similar parts throughout the different figures of the drawings.

Referring to Figs. 1 and 2, my invention as shown is embodied in a unitary structure divided into an upper evaporating-chamber 75 A, a lower water-chamber B, and an intermediate combustion-chamber C. The said boiler is desirably formed of boiler-plate, the upper chamber A comprising a top wall 1, secured to a cylindrical wall 3. The lower wall 80 of the chamber is formed by a diaphragm or partition 2, which is secured at its peripheral margins to the wall 3. The lower or water chamber B is provided with a concave bottom wall 4 and a cylindrical wall 6, the top wall 85 of said chamber being formed by a diaphragm or partition 5. The chamber B of the boiler is sunk within and surrounded by a closed wall D, composed of a suitable material, such as fire-clay, having heat-retaining properties 90 and which is provided with air-spaces D'. Said wall D incases the combustion-chamber C and extends a slight distance above the same, where juncture is effected with the cylindrical wall 3. Near the upper end of said 95 wall D and at opposite points the same is provided with an inlet and an outlet 7 and 8, respectively, whereby the products of combustion 100 are conveyed and delivered for passage through the combustion-chamber. The said structure is supported in place upon standards d, resting upon foundation parts d'. The combustion-chamber C is provided with a plurality of vertically-disposed tubes 9, extending between the partition-walls 2 and 5 105 and connecting said chambers A and B. Said tubes are spaced apart and generally distributed throughout the chamber in a manner to be engaged and played upon by the products of combustion in their passage through the 110 chamber C. I provide, as shown, an improved means for admitting the feed-water,

which desirably consists of the following parts. Near the center of the combustion-chamber I provide a relatively enlarged feed - water tube 10, which extends, like the tubes 9, from 5 the lower wall 5 to the upper wall 2. It will be seen that said tube is located in a position to be acted on effectively by the products of combustion, as it is directly in the path of travel of the latter. I desirably provide a 10 tube 11, which is located within the tube 10 and which is of slightly less diameter than the same, the said tube 11 being out of contact throughout its length with the tube 10 and chamber C and extending slightly beyond the 15 same above and below. Said tube is desirably supported in place by inclined rods 12. The upper end of said tube 11 is provided with an annular flange 13, which slightly overhangs the tube 10 and is centrally apertured. Water is 20 introduced to the boiler by means of a feed-pipe 14, which enters the chamber A through the side wall 3 and extends to a central position in said chamber, where it is preferably bent at right angles and is projected downwardly into the tube 11. The said feed-water pipe may be controlled in any suitable manner and connected with a convenient source of supply. A blow-off pipe 15, controlled by a suitable valve, is connected to 25 the lower wall 4 of the chamber B, as shown in Fig. 1. The water - level is preferably maintained at a point above the overhanging flange 13.

It will be noted by reference to Fig. 2 that 30 as the tubes 9 are of relatively reduced diameter with respect to the tube 11 the water in said tubes 9 will be more quickly heated and will also be heated to a higher temperature than the water in the tube 11, the result 35 being that the water in the tubes 9 will rise more quickly than in the tube 11. It will be further obvious that the water above the diaphragm 2 will be of a relatively lower temperature than that in the tubes 9 and will be 40 displaced thereby and forced downwardly through the tube 11 to the chamber B, this circulation being continuous throughout the operation of the boiler. The water passing downwardly is prevented to a great extent 45 from entering the tube 10 by reason of the overhanging flange 13. This results in the water in the tube 10 having little or no circulation, and thereby attaining a very high temperature, the heat units being effectively 50 transmitted to the tube 11. It will thus be seen that the tube 10 thereby acts as an effective feed-water heater. As water is admitted through the feed-pipe 14 it is directed downwardly through the tube 11 and is subjected to the relatively high temperature of 55 the water in said tube 10 before it reaches the chamber B. The feed-water is admitted directly to the boiler and is immediately acted upon by the feed-water heater, so that the 60 temperature of the contents of the boiler ad-

70 jacent the steam-space and near the heating-tube 9 is not reduced. This is a very great advantage, inasmuch as it entirely avoids the necessity of heating the water before the same is admitted to the boiler.

75 Next, referring to Fig. 3, it will be noted that in the form therein shown deflecting-partitions 16 and 17 are provided, which cause the flames or products of combustion to travel in a more circuitous path than in the form shown in Figs. 1 and 2. Said deflecting-partitions desirably extend throughout the height of the chamber C and project in opposite directions and toward the center of said chamber. In the form shown one of said 80 walls 16 desirably extends to the circulating-tube 10, the latter being located at a point slightly at one side of the center of the chamber C. The remaining partition 17 desirably extends somewhat beyond the tube 10 and 85 so enlarges and extends the path of the products of combustion that the same travel throughout and play upon substantially all of the tubes 9. In the form shown in Fig. 3 the parts which are similar to the form shown 90 in Figs. 1 and 2 are designated by similar characters of reference, the structure differing from that shown in Fig. 2 only as hereinbefore described.

95 While in the constructions hereinbefore described I have shown a single boiler which is designed to be connected with a furnace and to deliver the products of combustion direct to the chimney, it will be understood that the device of my invention is not confined to this particular use and that the same may be and in some cases will desirably be constructed so that two or more boilers will be connected to utilize the products of combustion of a single furnace. In Fig. 4 is 100 shown a horizontal sectional view through the combustion-chambers of three connected boilers 18, 19, and 20, wherein the outer walls D are joined in a manner to form a main inlet-passage E, through which the furnace 105 delivers to boilers 18 and 19, and a connecting-passage F conveying the products of combustion delivered from the two alined boilers, as shown, to the third boiler 20, said products being transmitted therefrom through a 110 passage G direct to the chimney. I desirably provide a diaphragm H, which is arranged to deflect the products of combustion laterally and rearwardly to the oppositely-disposed alined boilers in a manner to cause 115 the greatest possible length of travel.

120 While I have herein shown and described specific embodiments of my invention, it will be understood that I do not wish to be limited to the precise constructions shown, as changes may be readily made therefrom without departing from the spirit of the invention.

125 Therefore what I claim, and desire to secure by Letters Patent, is—

130 1. A vertical boiler comprising a unitary

- structure provided with horizontal partition-walls forming a lower water-chamber, an upper evaporating-chamber, and an intermediate combustion-chamber, said combustion-chamber having an inlet and an outlet for the passage of products of combustion, a plurality of tubes located in the path of travel of said products of combustion and connecting said water and evaporating chambers, a circulating-tube centrally disposed within said combustion-chamber, a feed-water tube located within said circulating-tube and extending throughout the length thereof, said feed-water tube having on its upper end a flange overhanging said circulating-tube, and a feed-water pipe projecting downwardly within said feed-water tube. 5
2. In a vertical boiler the combination of a lower water-chamber, an upper evaporating-chamber, an intermediate combustion-chamber closed to said water and evaporating chambers, a plurality of tubes in said combustion-chamber connecting said water and evaporating chambers, a relatively enlarged circulating-tube for said combustion-chamber, a pair of deflecting-partitions extending on opposite sides of said inlet and outlet toward each other in said combustion-chamber, one of said partitions engaging said tube, the remaining partition being spaced apart permitting the products of combustion to travel in a circuitous path from said inlet to said outlet. 10
3. A feed-water heater for boilers of the class described comprising an outer water-tube, an inner tube inclosed by and separated from said outer tube, a feed-water pipe projecting downwardly in said inner tube, the latter having a flange overhanging the said outer tube. 15
4. In a vertical boiler the combination of a lower water-chamber, an upper evaporating-chamber, an intermediate combustion-chamber having horizontally-disposed ingress and egress passages causing the products of combustion to travel in a horizontal path from said ingress to egress passages. 20
5. In a vertical boiler the combination of a lower water-chamber, an upper evaporating-chamber, an intermediate combustion-chamber having horizontally-disposed ingress and egress passages relatively restricted with respect to said combustion-chamber causing the products of combustion to travel in a substantially horizontal path from said ingress to egress passages. 25
6. In a vertical boiler the combination of a lower water-chamber, an upper evaporating-chamber, a plurality of tubes connecting said water and evaporating chambers, an intermediate combustion-chamber having horizontally-disposed ingress and egress passages causing the products of combustion to travel in a horizontal path from said ingress to egress passages. 30
7. In a vertical boiler the combination of a lower water-chamber, an upper evaporating-chamber, a plurality of tubes connecting said water and evaporating chambers, an intermediate combustion-chamber having horizontally-disposed ingress and egress passages relatively restricted with respect to the combustion-chamber causing the products of combustion to travel in a substantially horizontal path from said ingress to egress passages. 35
8. In a vertical boiler the combination of a lower water-chamber, an upper evaporating-chamber, an intermediate combustion-chamber having an inlet and an outlet, a plurality of tubes connecting said water and evaporating chambers, deflecting-partitions extending from opposite sides of said outlet and inlet into said combustion-chamber, one of said partitions engaging a tube, the remaining partition being spaced apart causing the products of combustion to travel in a circuitous path from the inlet to the outlet. 40

In testimony whereof I affix my signature in presence of two witnesses.
